UNITED STATES PATENT OFFICE.

ARCHIBALD BARR AND WILLIAM STROUD, OF GLASGOW, SCOTLAND, ASSIGNEES TO
BARR AND STROUD, LIMITED, OF ANNIESLAND, GLASGOW, SCOTLAND.

MECHANICAL RELAY.

Application filed September 1, 1922. Serial No. 585,822.

To all whom it may concern:

Be it known that we, ARCHIBALD BARR and WILLIAM STROUD, subjects of the King of Great Britain and Ireland, and both of Caxton Street, Anniesland, Glasgow, Scotland, have invented new and useful Improvements 5 in Mechanical Relays, of which the following is a specification.

This invention refers to mechanical relays 10 of the type comprising a servomotor for driving apparatus offering considerable resistance or having much inertia, so as to keep the apparatus in conformity with indications sent by a transmitter to a receiver say, by means of a step-by-step transmitter and receiver, said receiver being itself incapable of driving the apparatus.

The servomotor to be used may comprise 20 any suitable type of motor (electric, hydraulic or other type), and for the purposes of this invention comprises a driven element and two driving elements, so arranged that with the motor in operation both driving elements may be allowed to run free, 25 in which case no motion is transmitted to the driven element but when one of the driving elements is stopped the other operates to transmit the drive, the motion thereby transmitted to the driven element being in 30 one sense when the one driving element is stopped and in the opposite sense when the other is stopped.

The apparatus to be driven and kept in conformity comprises a differential gear of 35 any suitable type (bevel wheel, lever or other type), one element of which is moved in accordance with indications of a receiver, while a second element is actuated by the driven element of the servomotor, whereby 40 motion is imparted to the third element of the differential gear by the receiver and motion in a counter sense is imparted to the third element by the servomotor, so that the third element when displaced from a 45 definite fiducial position by the action of the receiver is brought back to that position by the action of the servomotor. Thus the motion of the second element becomes a measure of the motion of the receiver.

50 This invention relates principally to the means for separately stopping the driving elements of the servomotor, and consists in the provision of control mechanism comprising a differential gear, to one element of which (the driving element) motion is

imparted forwards or backwards by the receiver, which motion is transmitted to one or other or momentarily to both of the other two elements (the driven elements) associated with means for controlling the motion of the two driven elements from a fiducial position in either a forward or backward direction, one of the driven elements being capable of restricted motion only of the extent required for actuating control gear provided for bringing into action and determining the direction of operation of the servomotor, and the other capable of extensive motion derived from the driving element, so that in operation the motion 60 produced for actuating the control gear occurs only when the parts are in the process of leaving or returning to the fiducial position. 65

An example of mechanism and modifications according to this invention will now be described with reference to the accompanying drawings, in which:—

Figure 1 is a key diagram.

Figure 2 is a side elevation representing 80 a scroll disc associated with the control mechanism, Figure 3 is a similar view representing another scroll disc.

Figure 4 is an elevation illustrating a 85 complete apparatus.

Figure 5 is an elevation and 6 is a plan of an apparatus more compactly arranged.

Figure 7 is an elevation showing a modification of the control mechanism.

In Figure 1, *d* designates a differential 90 comprising bevel wheels *e* & *e*¹, and *D* a differential gear comprising bevel wheels *E* & *E*¹. A receiver, say a step-by-step receiver, not shown, is arranged to rotate shaft *K* to which is fixed the spindle of planet wheel *j*. 95 The bevel wheel *e* is controlled by the servomotor, while bevel wheel *e*¹ is geared to planet wheel *J* of *D*, the spindle of *J* being fixed to shaft *A*. Fixed to bevel wheels *E* and *E*¹ respectively are scroll discs *F* and *F*¹, *F* being represented in Figure 2 and *F*¹ in Figure 3. Two pins *P* and *P*¹ engage respectively in these scrolls, the two pins move in unison being fixed respectively to arms *L* and *L*¹ connected to rock angularly 100 with a shaft *L*² carried by fixed bearings. The scroll disc *F* is connected to turn angularly with arms *H* & *H*¹, constituting holders which rock in unison, in such a manner that when pin *P* is in the position shown in 105

Figure 2, neither H nor H¹ holds the servomotor. The servomotor may be of any suitable type, for example, as follows:—C represents a shaft continuously driven in the appropriate direction by some form of motor not shown, and is the power shaft of the servomotor. Fixed to shaft C is the spindle of the bevel wheel 7 gearing with the bevel wheels 8 and 9. Toothed detent X and gear wheel 10 are connected to rotate with 8 and toothed detent Y and gear wheel 11 are connected to rotate with 9 (in Figure 4 the detents X and Y are carried by a shaft N and connected with 8 and 9 by gearing). Wheel 10 gears with wheel 12 and wheel 11 with 13 through an idle wheel 19. Bevel wheel 14 is fixed to 12 and bevel wheel 16 to 13. 15 is a further bevel wheel gearing with 14 and 16, the spindle of 15 being connected to rotate with shaft M. The three bevel wheels 14, 15 and 16 thus form an ordinary differential gear.

When both detents X and Y are free and revolving in the same sense, the wheels 12 and 13 will be revolving in opposite directions, owing to the presence of the idle wheel 19. Under these conditions the spindle of bevel wheel 15 fixed to shaft M will have very little tendency to turn. If, however, detent X is stopped by holder H, shaft M will rotate in the same sense as the power driven shaft C, whereas if Y is stopped by holder H¹ the direction of rotation of M will be reversed. Fixed to shaft M is a toothed wheel 17 gearing with wheel 18 connected to rotate with wheel e, so that, as M rotates, it drives bevel wheel J of the differential gear D by means of the parts 17 18 e j e¹ in such a way as to "wipe out" the motion of J produced by the action of the receiver associated with K.

When then the receiver turns shaft K the result will depend on the positions of pin P (Figure 2) and P¹ (Figure 3). If P and P¹ are nearer to the centres of their respective circles than that shown in the figures, wheel F will be locked by pin P while wheel F¹ will be driven in such a direction as to increase the radial distances of pins P and P¹. If, however, P and P¹ in the starting position are farther from the centres of their respective circles than that shown in the figures, wheel F will still be locked by pin P and all the drive will still be imparted to F¹ as before, but the locked position of F is (as will be seen from Figure 2) slightly different when P is nearer the centre than when it is farther from the centre.

It will be seen then that under all circumstances F only turns through a very small angle. Now the holders H and H¹ which stop detents X and Y respectively are geared directly to wheel F and the position is such that when the radial distance of P is greater than that of the sloping groove

G (Figure 2), X, say, is stopped, while Y is stopped when this radial distance is less than that of G. The direction of rotation of the power driven shaft C is so related to the other parts of the mechanism that the scroll disc F¹ is always driven in such a direction that P¹ (Figure 3) tends to move towards the stop S (Figure 3), thus e. g. if P¹ is nearer the centre than S the rotation is clockwise, while if P¹ is farther from the centre than S the rotation is counter-clockwise.

When the receiver shaft K is quite out of step with the shaft M, the pin P¹ (Figure 3) will not be at the stop S but the scroll disc F¹ will be angularly displaced with reference to the position of Figure 3, so that P¹ will lie upon either the inner or outer part of the scroll. Thus, the angular distance between F¹ and P¹ is a measure of the amount the shafts K and M are out of step. Under these conditions one or other of detents X or Y is stopped and shaft M is being driven in such a direction as to tend to bring it into conformity with the position of shaft K. As shaft M is being brought into conformity with K, wheel 17 drives F¹ (through the intervention of the parts 17, 18, e j e¹ J E¹) in such a direction as to bring P¹ to the stop S. The position shown in Figures 2 and 3 thus corresponds to the position of conformity of shafts K and M—the fiducial position or the position of conformity. If now K moves one step forward, F¹ being held by stop S, the drive will fall upon F (Figure 2) thus (by means of the sloping groove G) moving pin P nearer to or farther from the centre, and, as P and P¹ move in unison, as soon as or slightly before P leaves the groove G, P¹ is lifted past the stop S. If K moves a step backwards F is moved in the opposite direction and the effect is reversed.

The parts indicated in Figures 4, 5 and 6, are as indicated in the key diagram, Figure 1, so that the above description may be taken as applying to them also.

Various modifications of the mechanism for restoring the differential gear D to the position of conformity may be devised, e. g. instead of cutting the scrolls on flat discs F and F¹, these discs may be replaced, for example, by cylinders B and B¹ with parallel axes (Figure 7) and the pins P P¹ fixed to the rocking arm L L¹ by pins Q Q¹ fixed to a rod R capable of translation parallel to the axes of the cylinders in such a way that Q and Q¹ engage in suitably formed grooves cut on the cylindrical faces of B and B¹; thus the form of the groove on B may consist of two straight grooves each nearly half the length of the cylinder and parallel to its axis, the two grooves being angularly displaced to a small extent, while the grooves in the cylinder B¹ may consist of

two ordinary helices connected by a short groove parallel to the axis of B¹ as shown in Figure 7, this short groove taking the place of the obstruction S (Figure 3).

5 The cylinders of Figure 7 instead of having coincident axes may be arranged side by side with parallel axes in which case the long rod carrying the two pins may be replaced by a short rod with the pins on opposite sides of the rod.

10 It will be recognized that the scrolls on the driven elements need not consist of grooves, for example, they may consist of ribs or other suitable equivalent, and in 15 such cases instead of pins being provided for engagement with the scrolls equivalents suitable for the purpose may be used.

As an example of one application of this invention, the mechanism, see Figure 1, may 20 be used for steering a ship in conformity with motions of a receiver operated by control from a gyro-compass, in which case the gyro-controlled receiver would be connected to rotate shaft K, shaft C is continuously 25 rotated by a power drive, and shaft M is so operated by the power drive as to be brought into conformity with shaft K. Shaft M is capable of imparting a power drive.

30 We claim:

1. Apparatus comprising a first differential, a servo-motor, control mechanism, and servo-motor control gear operated by the control mechanism, the first differential comprising a first connection for communicating motion to its first element, a second connection for communicating motion from the servo-motor to its second element, and a third connection driven by its third element,

the control mechanism comprising a second 40 differential, the second differential comprising a first driving element driven by the third connection from the first differential, and two driven elements, one a restricted motion element, the other an extensive motion element, means for causing motion from the first driving element to be imparted to one or other or momentarily to both of the driven elements and when the restricted motion element is displaced operate to restore 50 it to its fiducial position and a connection from the restricted motion element to the servo-motor control gear, for the purposes set forth.

2. Apparatus comprising a first differential, 55 a servo-motor, control mechanism, and servo-motor control gear operated by the control mechanism, the first differential comprising a first connection for communicating motion to its first element, a second 60 connection for communicating motion from the servo-motor to its second element, and a third connection driven by its third element, the control mechanism comprising a second differential, the second differential 65 comprising a first driving element driven by the third connection from the first differential, and two driven elements, one a restricted motion element having a short 70 scroll, the other an extensive motion element having a long scroll, means moving in unison engaging with the scrolls, and a connection from the restricted motion element to the servo-motor control gear, for the purposes set forth.

ARCHIBALD BARR.
WILLIAM STROUD.
